UNITED STATES PATENT OFFICE.

GUY R. CALEY, OF SILESIA, MONTANA.

CUTTING DEVICE.

1,196,929.

Specification of Letters Patent. Patented Sept. 5, 1916.

Application filed January 12, 1916. Serial No. 71,736.

To all whom it may concern:

Be it known that I, GUY R. CALEY, a citizen of the United States, residing at Silesia, in the county of Carbon and State of Montana, have invented certain new and useful Improvements in Cutting Devices, of which the following is a specification, reference being had to the accompanying drawings.

This invention relates to certain improvements in cutting devices and has relation more particularly to a device of this general character especially designed and adapted for use in connection with the topping of beets or the like; and it is an object of the invention to provide a novel and improved device wherein the cutting operation is under control of the beet or the like to be operated upon.

It is also an object of the invention to provide a cutting device of this general character including a cutting member capable of adjustment relative to the article to be operated upon together with novel and improved means whereby the adjustment of the cutting member is automatic and under control of the article to be operated upon.

The invention consists in the details of construction and in the combination and arrangement of the several parts of my improved cutting device whereby certain important advantages are attained and the device is rendered simpler, less expensive and otherwise more convenient and advantageous for use, all as will be hereinafter more fully set forth.

The novel features of the invention will be carefully defined in the appended claims.

In order that my invention may be better understood, I will now proceed to describe the same with reference to the accompanying drawings, wherein—

Figure 1 is a view in side elevation of a cutting device constructed in accordance with an embodiment of my invention and shown in applied position; Fig. 2 is a longitudinal vertical sectional view taken through my improved cutting device as herein embodied; Fig. 3 is a fragmentary view, partly in elevation and partly in section, illustrating certain of the parts in a position different from the positions of the corresponding parts as illustrated in Fig. 2, the tension spring as disclosed in Fig. 2 being omitted; Fig. 4 is a view in top plan of

my improved cutting device; Fig. 5 is an 55 enlarged sectional view taken substantially on the line 5—5 of Fig. 4; Fig. 6 is a view in side elevation of the clutch member as herein embodied, the coacting shaft being shown in section; Fig. 7 is a fragmentary 60 view, partly in elevation and partly in section, illustrating a means whereby the trip, as herein embodied, may be longitudinally adjusted; and Fig. 8 is a fragmentary detail 65 elevational view illustrating the connection, as herein disclosed, for operating the deflecting member herein included.

As herein disclosed, C denotes the upper portion of a conveyer structure generally employed in connection with beet pullers for 70 lifting or elevating the beets after the same have been drawn from the ground and said conveyer C is adapted to deliver the beets in substantially a horizontal position between the inner stretches of the endless 75 aprons A traveling around vertical axes and operatively supported by the rear frame structure F. The frame F is of such design as will best meet the requirements and as the frame in its details forms no part of 80 my present invention, it is thought that a specific description thereof is unnecessary other than to state that the rear frame F is operatively supported by the shaft S on which is mounted the traction wheel W of 85 conventional construction and provided with the fixed gear G secured thereto in any desired manner.

As herein disclosed, each of the aprons A comprises the vertically aligned endless 90 sprocket chains 1 disposed around the sprockets 2 fixed to the opposite end portions of the vertically disposed shafts 3 and 4. The vertically aligned chains 1 are connected by the vertically disposed members 1^a which 95 may be wire of requisite gage or as desired. The shafts 3 are arranged adjacent the inner end of the rear frame F and are rotatably supported thereby in predetermined spaced relation transversely of the 100 frame F while the shafts 4 are rotatably supported by the outer ends of the frames 5. As herein disclosed, the frames 5 are substantially H-shape and have their inner ends loosely mounted upon the shafts 3 whereby 105 said frames 5 are capable of relative rocking movement in a horizontal plane. The upper end portions of the shafts 4 have pivotally en-

gaged therewith the inner end portions of the arms 6 which extend transversely of the frame H in opposite directions and have their outer or free end portions loosely disposed through the guides 7 suitably positioned upon the frame F. The frames 5 are normally maintained at the limit of their inward rocking movement through the medium of the expansible members 8, herein disclosed as conventional coil springs, surrounding the arms 6 and interposed between the sides of the frame F and the pins 9 carried by and disposed through the arms 6 at predetermined points intermediate the length thereof. I do not wish, however, to be understood as limiting myself to this particular automatic arrangement for maintaining the rock frames 5 normally at the limit of their inward relative movement.

Operatively supported by the frame F and in a horizontal plane above the rock frames 5 is the longitudinally disposed shaft 10 on which is mounted the hub 11 adapted to rotate therewith but capable of movement longitudinally thereof and the hub 11 has loosely engaged therewith the collar 12 provided with the bracket or clip 14 with which coacts the flexible member 17 preferably of wire of requisite gage having its extremities secured to the upper portions of the shafts 4, as indicated at 18. By this arrangement, it will be perceived that as a beet or other article is carried rearwardly by the aprons A, the frames 5 will be rocked outwardly in accordance with the size or thickness of the beet and draw the hub 11 inwardly so that the knife K carried by said hub 11 will cut the top from the beet and preferably at a point in close proximity to the lower crown leaf. It is well known that the larger the beet the thicker the crown and that a large beet has from one to two inches more crown to be cut off than a small beet. It is for the purpose of compensating for the different sizes of crowns that the hub 11 is adjusted longitudinally of its shaft under the influence of the beet traveling between the aprons A.

The outer end of the shaft 10 is provided with a beveled gear 19 adapted to be engaged by the arcuate beveled rack 20 carried by a face of the disk 21 loosely mounted upon the shaft 22 supported by and disposed transversely of the frame F. The rack 20 is of a length as to cause one complete revolution of the shaft 10. Fixed to the shaft 22 and at a side of the disk 21 opposite to the rack 20 is the clutch member 23 provided with the annular flange 24 disposed inwardly relative to the disk 21 and provided with the equidistantly spaced internal sockets or recesses 25 adapted to receive the roller 26 carried by the rock arm 27 pivotally supported intermediate its length, as at 28, by the hub 29 of the disk 21. It is to be ob-

served that the roller 26 is arranged to one side of the rock arm 27 so that it may operatively engage a socket or recess 25 of the clutch member 23 and to afford no obstruction to the rotation of the clutch member 23 when said roller 26 is unseated from a socket or recess 25. It will be self-evident that with the roller 26 engaged within a socket or recess 25, the disk 21 will be caused to rotate in unison with the clutch member 23 and in the same general direction.

As herein embodied and as particularly illustrated in Fig. 5, the disk 21 is provided with an annular flange 30 concentric to the shaft 22 and extending in a direction toward and adapted for engagement with the flange 24 of the clutch member 23 and the flange 30 is provided with an elongated slot 31 through which the outer end of the rock arm 27 is directed so that said rock arm may be engaged by the trip arm 32 to be herein-after more particularly referred to. The trip arm 32 serves to unseat the roller 26 from within a socket or recess 25 while the expansible member 33 interposed between the hub 29 of the disk 21 and the inner end of the rock arm 27 serve as an automatic means for positioning the roller 26 within a socket or recess 25 when the trip arm 32 is disengaged from the outer end of the rock arm 27. As herein embodied, the expansible member 33 constitutes a conventional coil spring of requisite strength. In the present embodiment of my invention, the trip arm 32 is affixed to one extremity of the shaft 34 rotatably supported by the outer bearing 35 for the shaft 10. The shaft 34 is also provided with the rock arm 36 having pivotally engaged with its outer or free extremity the elongated bar 37 substantially horizontally disposed, and pivotally engaged as at 38 with the bar 37 at a predetermined point intermediate its length is the upper end portion of the operating arm 39 substantially vertically disposed and mounted intermediate its length for rocking movement upon the shaft 22, the lower end of the arm 39 is provided with the inwardly disposed elongated finger 40 terminating normally adjacent to and slightly inwardly of the discharge ends of the aprons A. It will thus be seen that as a beet or the like is carried rearwardly by the aprons A, the beet will contact with the finger 40 and force the arm 39 rearwardly whereby the trip arm 32 will be disengaged from the rock arm 27 so that the knife K will be caused to rotate and top the beet.

It is to be noted in Figs. 2 and 7 that the finger 40 is capable of longitudinal adjustment relative to the arm 39 as the connected extremity of the finger 40 is threaded, as at 41, through the laterally directed lug 42 carried by the lower end portion of the arm 39. This longitudinal adjustment of the

finger 40 affords a means to readily regulate the amount of top to be cut from the beet in contradistinction to the rocking movement of the frames 5 which regulate the amount 5 of the top to be cut according to the size of the beet. In order to assure the beet carried between the aprons A engaging the finger 40, I find it of advantage to employ vertically aligned guides disposed longitudinally of the 10 frame F between the rock frames 5 and, as herein embodied, said guides comprise the endless chains 41 operatively engaged with the gears 42 fixed to the shafts 61 disposed transversely of and supported by the frame 15 F adjacent its forward end, and the chains 41 are also operatively engaged with the sprockets 42^a mounted in the outer or free ends of the frames 62 pivotally engaged with the shafts 61, so that said chains 41 are capable 20 of relative movement in order to adapt themselves to beets of varying sizes.

As herein disclosed, the inner stretches of the chains 41 are normally arranged in forwardly converging planes as is particularly 25 illustrated in Fig. 2, and said chains are maintained in their normal position through the medium of the arms 63 pivotally engaged with the frames 62 and disposed in opposite directions and extending through 30 the transverse beams 64 of the frame F, and interposed between said beams 64 and the collars 65, carried by the arms 63, are the expansible members 66 herein disclosed as conventional coil springs which permit a 35 ready separating movement of the chains 41 but serve to maintain the same normally at the limit of their inward movement, said inward movement being limited by the stops 67 disposed through the outer ends of the 40 arms and coacting with the outer faces of the beams 64.

It is also a purpose of my invention to employ a deflecting member which serves to throw the severed tops in one direction and 45 the beets proper in a second direction and, as herein embodied, the deflecting member D is mounted upon the rock shaft 43 and is positioned below the finger 40 and is adapted to be swung from one position to the other 50 through the medium of the arm 39. As disclosed in Figs. 1 and 2, the deflecting member D is in a position to guide the severed tops. As is particularly illustrated in Figs. 1, 2 and 8, the shaft 43 is provided with rock 55 arms 44 each of which having engaged therewith the roller 45 which is capable of adjustment longitudinally of the rock arm 44 and said roller is positioned within the longitudinally disposed slot 46 formed in the 60 lower end of the bar 47, the upper end of said bar 47 being pivotally engaged as at 47^a, with the bar 39^a directly connecting the bar 39, the extremities of said bar 39^a and bar 39 being further connected 65 by the bracing members 68. It will be ob-

served that as the bar 39 is initially forced outwardly, the slots 46 will prevent rocking movement being imparted to the shaft 43. This arrangement is provided so that the position of the deflecting 70 member will not be changed until the severed top has been properly deflected. In order that sufficient rocking movement may be imparted to the arm 39 to cause the bars 47 to swing the deflecting member D into its 75 second position, as illustrated in Fig. 3, I provide the disk 21 with the roller 48 adapted to engage the finger 49 depending from the bar 37 whereby said bar 37 is positively moved rearwardly under the influence of the 80 shaft 22 and as the disk 21 continues to rotate the roller 48, as indicated by dotted lines in Fig. 3, will engage the lower end of the inwardly and downwardly inclined arm 50 carried by the outer end of the arm 37 85 whereby outward movement will be positively imparted to the arm 37 under the influence of the shaft 22 to throw the deflecting member D back to the position illustrated in Fig. 3 to engage the rock arm 27 90 to disengage the disk 21 from the clutch member 23. I also find it of advantage to employ the retractable tensioning member 51 having one extremity secured to the inner end of the arm 37 with its opposite end secured to the laterally and outwardly directed arm 52 carried by the bar 39 at a point above the shaft 22. This tensioning spring serves to assure the trip bar 32 being maintained in operative contact with the 95 rock arm 27 during the period the disk 21 is 100 rock arm 27 during the period the disk 21 is 105 idle.

The shaft 22 is adapted to continuously operate during the travel of the machine with which my invention is employed and 110 for this purpose has one end portion provided with the gear 53 operatively engaged with the idle gear 54 rotatably supported by the sprocket chain 55 also operatively engaged with the shaft 56 disposed transversely of the frame F at the inner end portion thereof, said shaft 56 being also operatively connected, as at 57, with the upper ends of the shafts 3 whereby the requisite travel is imparted to the endless aprons A. 115 The shaft 56 is also operatively engaged, as at 58, with the stub shaft 59 supported by the frame 1 and, as herein disclosed, said shaft 59 is provided with a gear wheel 60 in mesh with the gear G hereinbefore referred to, whereby it will be perceived that my improved cutting device, as herein disclosed, is driven from the traction wheel W. It is also to be noted that the chains 41 are 120 positively driven, and as herein embodied, the upper shaft 61 is provided with a gear 69 operatively engaged with a gear 70 carried by the shaft 56, and the shaft 56 has also operatively engaged therewith the sprocket chain 71 operatively engaged with 125 130

the lower shaft 42 whereby it will be perceived that the chains 41 will be caused to rotate in unison and in the proper directions.

From the foregoing description, it is thought to be obvious that a cutting device constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

In view of the foregoing, it will be understood that the beet or the like to be topped will pass between the rock frames 5 with the tops forwardly directed and that said beet will be carried rearwardly by the aprons A and properly guided by the chains 41. It will also be self-evident that as the beet or the like passes between the rock frames 5, that the free ends of said frames will be caused to separate a distance in accordance with the size of the beet. The separating movement of the free ends of the frames 5 will draw the knife K inwardly in a manner which has hereinbefore been fully described, so that said knife will cut the top from the beet at a point in close proximity to the lower crown leaf. It will also be readily appreciated that the beet will contact with the finger 40 to force the same rearwardly, whereby the trip arm 32 will be disengaged from the rock arm 27 so that the knife K will be caused to rotate and top the beet. After the top is severed it will fall upon the deflecting member D to assure the proper discharge of the severed top and that upon continued rearward movement of the finger 40, the deflecting member D will be caused to assume the position particularly shown in Fig. 3, and in a manner as has hereinbefore been set forth and upon which the beet drops for a purpose which is believed to be self-evident.

I claim:

1. A device of the character described comprising a cutting member, a feeding means, means operating under the influence of an article carried by the feeding means to adjust the cutting member relative to the discharge end of the feeding means, and means under control of the article carried by the feeding means for imparting movement to the cutting member.

2. A device of the character described comprising a cutting member, a feeding means, means operating under the influence of an article carried by the feeding means to

adjust the cutting member relative to the discharge end of the feeding means, and means for causing the cutting member to operate upon the article carried by the feeding means.

3. A device of the character described comprising a feeding means, a cutting member mounted for movement relative to the discharge end of the feeding means, and means carried by the feeding means coacting with the cutting member for moving the cutting member relative to the feeding means under the influence of the article carried by the feeding means.

4. A device of the character described comprising a feeding means, a cutting member movable in a plane intersecting the path of travel of an article carried by the feeding means, and means carried by the feeding means coacting with the cutting member and operable under the influence of an article carried by the feeding means for moving the cutting member toward the discharge end of the feeding means.

5. A device of the character described comprising a feeding means, a cutting member movable in a plane intersecting the path of travel of an article carried by the feeding means, means carried by the feeding means coacting with the cutting member and operable under the influence of an article carried by the feeding means for moving the cutting member toward the discharge end of the feeding means, and automatic means for imparting movement to the cutting member in an opposite direction.

6. A device of the character described comprising a feeding means, said feeding means consisting of coacting endless aprons having their discharge ends capable of relative lateral movement, a cutting member mounted for sliding movement relative to the discharge ends of the aprons, means carried by the discharge ends of the aprons and coacting with the cutting member for imparting sliding movement to the cutting member upon outward lateral movement being imparted to the discharge ends of the aprons.

7. A device of the character described comprising a feeding means, said feeding means consisting of coacting endless aprons having their discharge ends capable of relative lateral movement, a cutting member mounted for sliding movement relative to the discharge ends of the aprons, means carried by the discharge ends of the aprons and coacting with the cutting member for imparting sliding movement to the cutting member upon outward lateral movement being imparted to the discharge ends of the aprons, and automatic means for normally maintaining the discharge ends of the aprons at the limit of their inward lateral movement.

8. A device of the character described comprising a feeding means, said feeding means consisting of coacting endless aprons having their discharge ends capable of relative lateral movement, a cutting member mounted for sliding movement relative to the discharge ends of the aprons, means carried by the discharge ends of the aprons and coacting with the cutting member for imparting sliding movement to the cutting member upon outward lateral movement being imparted to the discharge ends of the aprons, and means operable under the influence of an article carried by the feeding means for causing the cutting member to travel in a plane intersecting the path of travel of the article carried by the feeding means.
9. A device of the character described comprising a feeding means, said feeding means consisting of coacting endless aprons having their discharge ends capable of relative lateral movement, a cutting member mounted for sliding movement relative to the discharge ends of the aprons, means carried by the discharge ends of the aprons and coacting with the cutting member for imparting sliding movement to the cutting member upon outward lateral movement being imparted to the discharge ends of the aprons, and a guiding means for an article carried by the feeding means.
10. A device of the character described comprising a feeding means, said feeding means consisting of coacting endless aprons having their discharge ends capable of relative lateral movement, a cutting member mounted for sliding movement relative to the discharge ends of the aprons, means carried by the discharge ends of the aprons and coacting with the cutting member for imparting sliding movement to the cutting member upon outward lateral movement being imparted to the discharge ends of the aprons, and a guiding means for an article carried by the feeding means.
11. A device of the character described comprising a feeding means, said feeding means consisting of coacting endless aprons having their discharge ends capable of relative lateral movement, a cutting member mounted for sliding movement relative to the discharge ends of the aprons, means carried by the discharge ends of the aprons and coacting with the cutting member for imparting sliding movement to the cutting member upon outward lateral movement being imparted to the discharge ends of the aprons, and a guiding means for an article carried by the feeding means, said guiding means being positioned intermediate of the aprons.
12. A device of the character described comprising a feeding means, said feeding means consisting of coacting endless aprons having their discharge ends capable of relative lateral movement, a cutting member mounted for sliding movement relative to the discharge ends of the aprons, means carried by the discharge ends of the aprons and coacting with the cutting member for imparting sliding movement to the cutting member upon outward lateral movement being imparted to the discharge ends of the aprons, and a guiding means for an article carried by the feeding means, said guiding means being positioned intermediate of the aprons and disposed longitudinally thereof.
13. A device of the character described comprising a feeding means, a driven shaft, an operating member loosely mounted on the shaft, a rotary cutter, coacting means carried by the operating member and the cutter for rotating the cutter upon rotation of the disk, a clutch member fixed to the shaft and coacting with the disk, a trip arm coacting with the clutch for maintaining the same out of engagement with the disk, a rock arm operatively engaged with the trip arm whereby said trip arm is disengaged from the clutch upon the rock arm being moved in one direction, and a finger carried by the rock arm and terminating adjacent the discharge end of the feeding means and adapted to be engaged by an article carried by the feeding means for imparting the requisite movement to the rock arm for releasing the trip arm from the clutch member.
14. A device of the character described comprising a feeding means, a driven shaft, an operating member loosely mounted on the shaft, a rotary cutter, coacting means carried by the operating member and the cutter for rotating the cutter upon rotation of the disk, a clutch member fixed to the shaft and coacting with the disk, a trip arm coacting with the clutch for maintaining the same out of engagement with the disk, a rock arm operatively engaged with the trip arm whereby said trip arm is disengaged from the clutch upon the rock arm being moved in one direction, and a finger carried by the rock arm and terminating adjacent the discharge end of the feeding means and adapted to be engaged by an article carried by the feeding means for imparting the requisite movement to the rock arm for releasing the trip arm from the clutch member, said finger being capable of longitudinal adjustment.
15. A device of the character described comprising a feeding means, a cutting member adapted to travel in a plane intersecting the path of travel of an article carried by

the feeding means, a driven shaft, a disk loosely mounted on the driven shaft, coacting means carried by the cutting member and the disk for imparting movement to the 5 disk upon rotation of the disk, a clutch member fixed to the shaft and coacting with the disk, a trip arm coacting with the clutch member for maintaining the same out of engagement with the disk, a rock arm operatively engaged with the trip arm and serving to throw the same out of engagement 10 with the clutch member upon movement in one direction, a member carried by the rock arm adapted to be engaged by an 15 article carried by the feeding means for imparting the requisite movement to the rock arm to disengage the trip arm from the clutch member, a deflecting member positioned below the discharge end of the feeding 20 means and capable of rocking movement, an operating arm coacting with the rock arm and the deflecting member, and means carried by the disk for imparting rocking movement to the rock arm in addition 25 to the movement imparted to the rock arm under the influence of an article carried by the feeding means.

16. A device of the character described comprising a feeding means, a cutting member adapted to travel in a plane intersecting the path of travel of an article carried by the feeding means, a driven shaft, a disk loosely mounted on the driven shaft, coacting 30 means carried by the cutting member and the disk for imparting movement to the disk upon rotation of the disk, a clutch member fixed to the shaft and coacting with the disk, a trip arm coacting with the clutch member for maintaining the same out of engagement with the disk, a rock arm operatively engaged with the trip arm and serving to throw the same out of engagement 35 with the clutch member upon movement in one direction, a member carried by the rock arm adapted to be engaged by an article carried by the feeding means for imparting the requisite movement to the rock arm to disengage the trip arm from the clutch member, a deflecting member positioned 40 below the discharge end of the feeding means and capable of rocking movement, an operating arm coacting with the rock arm and the deflecting member, and means carried by the disk for imparting 45 movement to the rock arm in addition to the movement imparted to the rock arm under the influence of an article carried by the feeding means.

17. A device of the character described comprising a feeding means, said feeding means consisting of coacting endless aprons 5 having their discharge ends capable of relative lateral movement, a cutting member mounted for sliding movement relative to the discharge ends of the aprons, means carried by the discharge ends of the aprons and coacting with the cutting member for imparting sliding movement to the cutting member upon outward lateral movement being imparted to the discharge ends of the aprons, and a guiding means for an article 10 carried by the feeding means, said guiding means being positioned intermediate of the aprons and disposed longitudinally thereof and arranged in planes converging toward the discharge end of the feeding means, said guiding means being capable of separating movement under the influence of an article passing therebetween.

18. A device of the character described comprising a feeding means, said feeding means consisting of coacting endless aprons 15 having their discharge ends capable of relative lateral movement, a cutting member mounted for sliding movement relative to the discharge ends of the aprons, means carried by the discharge ends of the aprons and coacting with the cutting member for imparting sliding movement to the cutting member upon outward lateral movement being imparted to the discharge ends of the aprons, and a guiding means for an article 20 carried by the feeding means, said guiding means being positioned intermediate of the aprons and disposed longitudinally thereof and arranged in planes converging toward the discharge end of the feeding means, said guiding means being capable of separating movement under the influence of an article passing therebetween.

19. A device of the character described comprising a feeding means, said feeding means consisting of coacting endless aprons 25 having their discharge ends capable of relative lateral movement, a cutting member mounted for sliding movement relative to the discharge ends of the aprons, means carried by the discharge ends of the aprons and coacting with the cutting member for imparting sliding movement to the cutting member upon outward lateral movement being imparted to the discharge ends of the aprons, endless guide chains positioned intermediate the aprons with their inner stretches normally disposed on forwardly converging planes, yieldable means for maintaining the guide chains in their normal 30 position, and means for imparting movement to the guide chains.

In testimony whereof I hereunto affix my signature in the presence of two witnesses.

GUY R. CALEY.
